UNITED STATES PATENT OFFICE.

JACOB GREENWALD, OF PHILADELPHIA, PENNSYLVANIA.

DESIGN FOR A STOCKING.

Application filed August 9, 1923. Serial No. 6,990. Term of patent 3½ years.

To all whom it may concern:

Be it known that I, JACOB GREENWALD, a citizen of the United States, residing at the Majestic Hotel, Broad and Girard Avenues, city of Philadelphia, county of Philadelphia, and State of Pennsylvania, have invented a new, original, and ornamental Design for a Stocking, of which the following is a specification, reference being had to the accompanying drawing, forming part thereof.

The figure is a view in perspective of the stocking, showing my new design of fabrics of contrasting colors and the back seam and the usual reinforcement obliterated and the contrasting color extended along the foot to the toe.

I claim:

The ornamental design for a stocking, as shown and described.

JACOB GREENWALD.
